(57) **CLAIM**

The ornamental design for a portable vehicle humidifier, as shown and described.

DESCRIPTION

FIG. 1 is a perspective view of the portable vehicle humidifier having a lighter socket plug-in and a flexible discharge line which is bent upwardly for humidity discharge.

FIG. 2 is a left side view of the portable vehicle humidifier shown in FIG. 1.

FIG. 3 is a plan view of the portable vehicle humidifier.

FIG. 4 is a front view of the portable vehicle humidifier.

FIG. 5 is an exploded perspective view of the portable vehicle humidifier. The top portion is unscrewed from the bottom portion; and,

FIG. 6 is an exploded front view of the portable vehicle humidifier.

The flexible discharge line is shown fragmented to indicate indeterminate length.
